UNITED STATES PATENT OFFICE.

C LUTHER BROWN, OF CHANDLER, OKLAHOMA.

TATTING DEVICE.

1,241,917.

Specification of Letters Patent.

Patented Oct. 2, 1917.

Application filed January 2, 1917. Serial No. 140,251.

To all whom it may concern:

Be it known that I, C LUTHER BROWN, a citizen of the United States, residing at Chandler, in the county of Lincoln and 5 State of Oklahoma, have invented certain useful Improvements in Tatting Devices, of which the following is a specification, reference being had therein to the accompanying drawing.

10 The present invention relates to a machine for use in tatting work, and is adapted to be used for tying knots and the like in a quick and efficient manner.

The present invention has for an object 15 to provide a machine or device of this nature which may be held in one hand and moved back and forth around one side of a loop or thread to facilitate the tying of the thread in the knot and to insure the even 20 and uniform knotting of the same.

It is another object of the present invention to provide a device of this character which is relatively light in weight, may be 25 economically manufactured and which comprises but relatively few parts requiring no adjustment or attention.

Further objects and advantages of this invention will be more particularly pointed out in the following description of the present 30 preferred embodiment, the same being illustrated in the accompanying drawings, wherein:—

Figure 1 is a perspective view of the improved device, showing its application and 35 use.

Fig. 2 is a top plan view of the device, showing in full and in dotted lines the various positions of the loop with respect to the device as the latter is operated through 40 the loop.

Fig. 3 is a detail sectional view of the shuttle of the device.

Fig. 4 is a transverse section taken through the holder and the shuttle showing the loose 45 mounting of the shuttle in the holder to permit the thread to pass around the opposite sides of the shuttle.

Referring to this drawing, 10 designates a handle which is forked at its outer end to 50 provide opposed prongs 11 and 12. The prongs 11 and 12 are provided in their inner opposite faces with longitudinally extending grooves or recesses 13 which are closed at their opposite ends, and into which 55 are fitted flanges 14 projecting from the opposite sides of a shuttle 15. The shuttle 15

has opposite tapering ends 16 and 17 which project respectively outwardly from the forked end of the handle and inwardly therebetween, as shown in Fig. 2. 60

The shuttle 15 is provided at its intermediate portion with a vertical socket or recess into which may be fitted a bobbin 18 upon which the thread 19 is adapted to be wound. The bobbin 18 is adapted to be 65 placed vertically in the socket or recess in the shuttle and has on its upper end serrations or teeth 20 which are inset or spaced inwardly from the peripheral edge of said bobbin, and with these serrations or teeth 70 is adapted to engage a pawl 21 which has its pivot 22 disposed a considerable distance inwardly in the top of the shuttle 15 so that when the pawl is released from the serrations or teeth 20 it engages with the peripheral edge of said bobbin concentrically with 75 respect to the serrations or teeth and thereby holds the bobbin within the shuttle for the rotation of the same. When the pawl 21 is locked with the teeth or serrations 20 the 80 bobbin is held against rotation. A spring 23 is seated in the bobbin 15 and engages 85 against the outer finger-engaging end of the pawl 21 to urge the inner end thereof yieldably against the serrations or teeth 20. The pivotal mounting of the pawl 21 permits it to move upwardly and outwardly when the finger-engaging end is depressed so as to bring the pawl out of locking engagement 90 with the serrations or teeth 20 and to resting position upon the peripheral edge of the bobbin 15 concentrically with respect to said serrations or teeth. The stem of the bobbin 18 may be provided with an opening 24 therethrough to receive one end of the thread 95 19 for holding the latter in place. The shuttle 15 is provided with a thread opening 25 which leads upwardly from an intermediate portion of the socket to the upper face of the bobbin, and through which the free 100 end of the thread is adapted to be passed.

The shuttle 15 is provided, in the bottom thereof, with a stepped bearing 26 into which fits a depending projection 27 formed on the lower end of the bobbin 18 105 for supporting the bobbin and for permitting the free turning thereof in the socket.

In use, the end of the thread 19 is grasped between the thumb and forefinger, and the thread is then looped outwardly over the 110 remaining fingers of the hand, the latter being extended outwardly substantially

straight. This strand 28, or the thread between the thumb and forefinger, and the remaining fingers constitutes one side of a loop, the opposite side being turned about 5 the fingers and being caught between the thumb and forefinger, as shown at 29 to securely hold the loop. The thread from the bobbin extends outwardly through the opening 25 in the shuttle, as shown at 30 10 and leads to the top of the loop. The device is now moved forwardly by the opposite hand to engage the strand 28 between the prong 12 and the outer pointed end 16 of the shuttle, the strand 25 passing freely 15 between the shuttle and the prong 12 by virtue of the enlargement of the recess 13. The inner end of the fork is rounded, as at 31 so as to direct the strand or thread 28 around to the opposite side of the fork 20 and against the prong 11. The device is now drawn backwardly and the strand 25 passes between the prong 11 and the rear pointed end 17 of the shuttle and is guided thereby into the recess 13. When the device 25 is drawn back to its fullest extent the strand 25 is again free from the device. During this operation the strand 30 of the thread is carried by the shuttle 15 around the strand 28 so as to form a knot or tie. 30 It will be noted from Fig. 1 that this operation may be carried on rapidly and that the knotting or tying will be uniform and positive, so that the work produced will be of a neater and finer appearance than is 35 possible to obtain without the use of this device. It is of course understood that various changes and modifications may be made in the above specifically described construction, without departing from the 40 spirit of the invention, and only being restricted by the scope of the following claims.

Copies of this patent may be obtained for five cents each, by addressing the "Commissioner of Patents, Washington, D. C."

What I claim is:—

1. A device as specified comprising a handle forked at one end, a shuttle loosely 45 mounted in said forked end, and means for carrying a supply of thread in said shuttle.

2. A device as specified comprising a handle having a pair of spaced apart prongs 50 on its outer end, a shuttle loosely mounted between said prongs, a thread support mounted in the shuttle for carrying a quantity of thread, and means for tensioning the drawing out of said thread.

3. A device as specified comprising a 55 handle provided at one end with spaced apart prongs, a shuttle mounted on said prongs and having loose connection therewith to permit the passage of a strand of thread around the shuttle between the 60 prongs, a bobbin mounted for rotation in said shuttle and adapted to carry a supply of thread, and a spring pressed pawl mounted on the shuttle for engagement with said bobbin to retard the rotation thereof, and having one end projecting upwardly for engagement with the finger to release said pawl at times for permitting the free drawing out of the thread.

4. A device as specified comprising a 70 handle having a longitudinal slot in one end, a shuttle mounted in said end and having inner and outer tapering ends, means for carrying a supply of thread for the 75 shuttle, and a tension device on the shuttle to retard the feeding of said thread, said handle being adapted to be grasped and moved back and forth about one strand of a loop to twist the thread from the shuttle thereabout and direct said strand around 80 the shuttle in said slotted end of the handle.

In testimony whereof I affix my signature.

C LUTHER BROWN.
